UNITED STATES PATENT OFFICE.

SIMON SCHLANGEN, OF CHICAGO, ILLINOIS, ASSIGNOR TO THE ECONOMICAL BEER BUNG COMPANY, OF CHICAGO, ILLINOIS, A CORPORATION OF ILLINOIS.

FILLING APPARATUS FOR LIQUIDS.

No. 828,057.

Specification of Letters Patent.

Patented Aug. 7, 1906.

Application filed June 29, 1904. Serial No. 214,606.

To all whom it may concern:

Be it known that I, SIMON SCHLANGEN, a citizen of the United States, residing at Chicago, in the county of Cook and State of Illinois, have invented certain new and useful 5 Improvements in Filling Apparatus for Liquids, of which the following is a specification.

The apparatus of the present invention is designed more particularly for filling barrels, half-barrels, kegs, and other packages with liquid, such as beer, under pressure, and has for its objects to construct an apparatus employing a sealing-head, a filling-tube, and a connection between the sealing-head and a tank containing liquid and pressure for equalizing the pressure between the tank and a to-be-filled package for the inflow of liquid into the package to return to the tank the pressure supplied from the tank to the package with the added pressure originally contained in the sealed package, thereby maintaining the necessary amount of pressure in the tank with the normal head of liquid for operating the piston by which the filling-tube is moved, and thus obviate the necessity of admitting additional pressure from a source of supply into the tank; to construct a sealing-head and a filling-tube operative for the sealing-head to tightly close the filling-hole 30 of the package and for the filling-tube to enter the package, with a chamber in the sealing-head around the filling-tube and a valve-controlled passage leading therefrom and having communication with the pressure-containing space of the filling-tank for equalizing the pressure between the tank and the package before admitting liquid to the package; in constructing a sealing-head having therein a chamber surrounding a filling-tube, 35 with a passage leading from the chamber and a valve controlling the passage and automatically actuated with the movements of the filling-tube to open and close the passage for inducing and educting pressure into and out 40 from the package; to enable a single valve to control the movements of the filling-tube and through the movements of the filling-tube supply pressure to and exhaust pressure from the to-be-filled package, the educting of the 45 pressure occurring with the admission of liquid into the package; to control the induction and eduction of pressure into and out 50 from the package by a valve actuated auto-

matically by the rising and falling movements of the filling-tube through a trip mechanism, one section of which is connected with the valve and the other section with the filling-tube; to automatically open and close the controlling-valve for inducting and educting pressure into and out from the package irrespective of whether the package is a full barrel, half-barrel, quarter-barrel, or one-eighth barrel, thus giving a control of the pressure irrespective of the size of the package; to enable the piston of the cylinder for moving the filling-tube to be properly and fully lubricated; to enable the sealing-head to properly seat in the bung or filling hole of the package without liability of striking the edge of the hole and being thereby prevented from fully seating; to fully control the movements of the filling apparatus by a single handle or lever and a main controlling-valve, thereby insuring against mistakes in operating the apparatus; to simplify and improve the apparatus as regards the control of the pressure between the filling-tank and the to-be-filled package and as to the admission of liquid into the package, and to improve generally the construction and arrangement of the devices which enter into the apparatus as a whole.

The invention consists in the features of construction and combinations of parts hereinafter described and claimed.

It is to be understood that the apparatus can have as many filling-tubes and actuating appliances therefor as may be desired, and for general use the apparatus is preferably supplied with three filling-tubes and their actuating appliances, though for the purpose of illustration a single filling-tube and its appliances is all that is deemed necessary to show in the drawings.

In the drawings, Figure 1 is a front elevation of the apparatus, showing a single filling-tube and its actuating appliances, the filling-tube and sealing-head being shown in their elevated position; Fig. 2, an elevation showing the supporting-frame for the sealing-head and filling-tube, with the sealing-head lowered and the filling-tube partly down; Fig. 3, a similar view to Fig. 2, showing the parts in the same position, except that the filling-tube has commenced its upward movement, the movement of the sealing-head and filling-tube illustrated in Figs. 1 and 2 being that

for use with a full barrel or package; Fig. 4, a similar view to Fig. 3, showing a stop-block on the piston-rod of the filling-tube for limiting the reciprocating movement of the tube for use in filling smaller-sized packages than barrels or full packages, the filling-tube and sealing-head being shown in their raised position; Fig. 5, a similar view to Fig. 4, with the sealing-head and filling-tube in their lower position; Fig. 6, a cross-section through the filling-tank with the supporting-frame for the filling-tube and sealing-head, the cylinder for actuating the piston of the filling-tube, and the pressure induction and eduction pipes for the cylinder in full elevation; Fig. 7, a vertical longitudinal section of the valve controlling the induction and eduction of pressure to the cylinder for the piston of the filling-tube; Fig. 8, a cross-section of the valve shown in Fig. 7, showing the plug in position to shut off the pressure from passing through the valve; Fig. 9, a cross-section of the valve shown in Fig. 7, with the plug turned to admit pressure to the upper end of the cylinder for the piston of the filling-tube and to educt pressure from the lower end of such cylinder; Fig. 10, a cross-section of the valve shown in Fig. 7, with the plug turned to induct pressure into the lower end of the cylinder for the piston of the filling-tube and to educt pressure from the upper end of such cylinder; Fig. 11, a sectional elevation of the sealing-head; Fig. 12, an elevation of the sealing-head with the cross bar or support thereof in section, showing the casing for the plug of the automatically-operated valve controlling the induction and eduction of pressure between the tank and the to-be-filled package; Fig. 13, an elevation of the interposed shell of the valve controlling the pressure between the tank and the to-be-filled package; Fig. 14, a similar view to Fig. 13, showing the interposed shell in a different elevation; Fig. 15, a sectional elevation of the shell of Fig. 13; Fig. 16, an elevation of the plug entered into the shell of Figs. 13, 14, and 15; Fig. 17, a detail of the screw for holding the plug of Fig. 16 in its shell or casing; Fig. 18, a detail, being an end elevation of the main shell of the valve controlling the pressure between the filling-tank and the to-be-filled package; Fig. 19, an end elevation of the interposed shell of Figs. 13, 14, and 15; Fig. 20, a horizontal section of the sealing-head and showing the valve controlling the pressure between the tank and the to-be-filled package; Fig. 21, an elevation of a sight-glass, showing the pressure-tube leading from the tank and connected therewith; Fig. 22, a detail, partly in section, of the sealing-head and filling-tube, showing the sight-glass and pressure-tube from the tank in elevation; Fig. 23, an elevation, partly in section, of the head at the upper end of the filling-tube; Fig. 24, an end elevation

tion of the head shown in Fig. 23; Fig. 25, a plan view of one of the trip-arms for automatically actuating the valve controlling the pressure between the tank and the sealing-head; Fig. 26, a side elevation of the trip-arm shown in Fig. 25; Fig. 27, a cross-section of the stop-block encircling the piston-rod for the filling-tube to limit the reciprocating movement of the filling-tube; Fig. 28, an elevation of the stop-block of the piston-rod; Fig. 29, a longitudinal section of the sealing-head with the filling-tube in elevation; Fig. 30, a detail, partly in section, of the plate of the frame; Fig. 31, a detail in section of the frame-plate and cylinder; Fig. 32, a detail in section to the sleeve of the sealing-head; Fig. 33, a detail in section of the head of the filling-tube, showing the means for opening and closing the valve of the filling-tube; Fig. 34, a detail, on an enlarged scale as compared with Figs. 1, 2, and 3, showing the construction and arrangement of the swinging frame and the trip for opening and closing the valve controlling the induction and eduction of pressure to the to-be-filled package; Fig. 35, a sectional elevation of the parts shown in Fig. 34; Fig. 36, a sectional plan view of the cross-head and supporting-bar at the lower end of the swinging frame; Fig. 37, a top or plan view of the cross-head at the lower end of the swinging frame with the tie-rods and the sight-glass in section; and Fig. 38, a detail, partly in section, of the valve controlling the induction and eduction of pressure between the filling-tank and the to-be-filled package.

The apparatus in the construction shown has at each end of the tank a leg or standard 1, each leg or standard having a rearward extension at its upper end furnishing supports 2, which receive and carry the filling-tank 3, one end of the tank having a solid head and the other end having a removable head to enable access to be had to the interior of the tank for cleansing or other purposes. The filling-tank 3 can be made of metal or other suitable material and of the capacity desired and can be of a length to receive and support three or more filling appliances, one of such appliances only being shown in Fig. 1, with a tank of the proper length to operate with a single filling appliance.

The end standards are connected on the front of the machine by a cross-plate 4, attached to which are bracket-plates 5, having a vertical section or portion and a horizontal section or portion, the latter of which has one-half 6 of a journal box or bearing, the other half 7 of the journal box or bearing being formed on a plate 8, attached to the horizontal portion or section of the bracket-plate. The journal boxes or bearings receive journal-pins 9, one at each end of a frame 10, supporting the frame, so that it is free to have a rocking movement fore and aft. Each side

bar of the frame 10 has secured thereto by bolts or otherwise a plate 11, on which is a half-box or journal-bearing 12, the companion half-box or journal-bearing 13 being formed 5 on the side plate or bar of the frame 10. The journal box or bearing of the frame 10 on each side has entered thereinto a journal 14, extending out from a plate 15, occupying the space within the frame 10 at the lower portion thereof. The plate 15 has depending therefrom side bars 16, each terminating at its lower end in a foot or head 17, and extending out from one foot or head 17 with a downward inclination is a bar 18, which is continued in a straight horizontal line by a bar 19, to which is connected one end of a bar 20, the other end of which is connected to the opposite foot or head 17, so that the bars 18, 19, and 20 form a cross plate or head for the lower end of the frame composed of the plate 15 and the side bars 16, which frame, by means of the journals 14, has a side rock or swing. This arrangement of the frame 10 with its end journals and the plate 15 with its side 25 journals operates to allow both a fore and aft rock and an end rock for the frame or support as a whole, by which the sealing-head can be brought into position to align with and operate properly to seal the bung or other 30 filling hole in the to-be-filled package in the event of such bung or other filling hole being out of direct alignment with the sealing-head and the filling-tube.

A rod 21 is located adjacent to each side bar 16, and each rod 21 at its upper end extends through the plate 15 and is free to slide in said plate, and, as shown, at the upper end of each rod 21 is a collar 21^a, furnishing a support for a weight, if needed, for the purpose 35 of causing the sealing-head to descend by gravity in sealing the bung or other filling hole. A cross head or bar 22, having at each end a socket 22^a, is attached by the sockets and suitable set screws or bolts 22^b to the 40 sliding rods 21 for the bar 22 to be located when the parts are in normal position just below the plate 15, and this bar 22 moves with the sliding rods. Each rod 21 at its lower end is secured in an ear 23^a of a cross 45 head or bar 23 and is held in place by a jam-nut 24 and a lock-nut 25, threaded onto the end of the rod on opposite sides of the ear. The cross head or bar 23 has an enlarged intermediate portion 26, having a central circu- 50 lar portion 27, on the upper side of which is an annular flange 28, having an exterior screw-thread, which receives a cap 29, within which is a gland or follower 30, which compresses a packing-ring or gasket 31, encircling the filling-tube 32, so as to make a tight joint around the filling-tube and prevent the escape of pressure around the tube. The filling-tube 32 passes through the end of the bar or plate 19, and the cross bar or plate 23 55 as located below the cross-head at the lower end of the side bar 16; so that the filling-tube is guided in its reciprocating movement by the plate 19. The under face of the circular head 27 of the cross bar or plate 23 has an annular rim 33, which receives a sealing-ring 34, 60 of rubber or other suitable material, which sealing-ring encircles a bearing or guide 36, threaded into a hole in the head 27, so that the lower end of the sleeve or guide 36 projects below the edge of the sealing-ring, and 65 this lower end of the sleeve or guide is curved and forms a face by which the sealing-ring can be seated without liability of being jammed or knocked to pieces, as the curved outer face of the sleeve or guide 36 forms a 70 guard and protection for the sealing-ring in the descent of the sealing-head to close the bung or other filling hole of the package. The sleeve or guide 36 on its inner face has a series of ribs 37, leaving passages 38 between 75 the exterior of the filling-tube and the interior face of the sleeve or guide 36, which passages at their lower end furnish openings 39, through which when the sealing-head is 80 down pressure can flow into and escape from 85 the package.

The hole in the sealing-head which receives the sleeve or guide 36 forms a chamber 40 around the filling-tube 32, and from this chamber 40 a passage 41 leads horizontally 90 in the cross bar or plate of the head and terminates in a passage 42, leading upwardly into a chamber 43, encircled by an annular flange 44 on the cross plate or bar of the sealing-head. A coupling-plug 45 is entered into 95 the annular wall or flange 44 and has entered thereonto the lower ring or band 46 of a frame carrying a sight-glass, which frame has side bars 47, connecting the lower ring or band 46 with an upper ring or band 48, between which 100 rings or bands 46 and 48 is located a sight-glass 49, held in place by coupling-heads 50, as usual in the construction of sight-glasses. The upper band or ring 48 has a side extension 48^a, into which is entered the lower end of a 105 tube 51, the upper end of which has attached thereto one end of a hose 52, the other end of which hose is connected to a plug 53, entered into the upper side of the filling-tank 3, so that pressure from the upper portion of the filling- 110 tank can flow through the hose 52, tube 51, sight-glass 50, and passage 41 into the chamber 40 and from the chamber 40 flow out through the channels or passages 38 and openings 39 into the to-be-filled package, and 115 pressure from the to-be-filled package can flow back through the openings 39, channels or passages 38, chamber 40, passage 41, sight-glass 50, tube 51, and hose 52 into the upper portion of the filling-tank. The induction of pressure from the filling-tank into the to-be-filled package occurs when the sealing-ring has effectually sealed the bung or filling hole of the package, and this induction of 120 pressure from the tank into the package adds 125 to the pressure of the tank. The induction of pressure from the filling-tank into the to-be-filled package occurs when the sealing-ring has effectually sealed the bung or filling hole of the package, and this induction of pressure from the tank into the package adds 130

- to the normal pressure in the package an amount of pressure from the tank to equalize the pressure between the tank and the to-be-filled package, and the induction of pressure from the to-be-filled package back into the filling-tank occurs as the liquid flows into the package, the inflow of the liquid forcing the air originally contained in the package and the added pressure from the tank back into the filling-tank, and the pressure derived from forcing the air originally contained in the sealed package and the added pressure from the tank from the package with the filling of the package back into the tank by the liquid furnishes the necessary power with the liquid in the tank at normal height, as hereinafter described, for operating the piston by which the filling-tube is raised and lowered.
- The upper end of the filling-tube is entered into an annular rim or flange 54 on the under side of a head 55, and the lower end of the filling-tube is closed by a valve 56 on the end of the rod 57, the upper end of which rod is connected by a pin or pivot 58 to an arm 59 within the head 55, which arm is mounted on a rock-shaft 60, supported in the side walls of the head 55, with its ends projecting beyond the side walls of the head and having secured thereto an arm 61, the outer end of which straddles one of the sliding rods 21, and this arm 61 is held normally depressed, so as to hold the arm 59 in a raised position and close the valve 56 by a spring 62, attached to studs or pins 63, projecting out from the exterior face of the head 55 in the construction shown. The descent of the head 55 with the filling-tube 32 carries down with it the arm 61, and when the filling-tube has descended to a point where the under face of the arm 61 contacts the foot or head 17 the further downward movement of the head 55 and the filling-tube will raise the arm 61, rocking the shaft 60 to carry down the outer end of the arm 59 and force the valve 56 away from the lower end of the filling-tube, allowing the liquid to pass through the filling-tube and flow into the package.
- The upper side of the head 55 has thereon a boss 64, in which is secured the lower end of a piston-rod 65, which rod passes up through the plate 15, and its upper end has secured thereto a piston 66, which traverses a cylinder 67, closed at its upper end by a cap or head 68 and entered at its lower end into an annular flange 69, secured to the plate 15 and in communication with a chamber 70, formed in the plate, which chamber has leading out therefrom, through one of the journals 14, a passage 71, into which is entered the end of a tube 72, the other end of which is connected with the casing of the main controlling-valve. A tube 73 leads from the opposite side of the casing of the main controlling-valve and extends upward and is entered into the top plate or cap 68 of the cylinder, so that pressure can be admitted to both ends of the cylinder and on opposite sides of the piston for the pressure on the upper side to force the piston down and with it the head 55 and the filling-tube 32 and for the pressure on the under side to raise the piston and with it the head 55 and the filling-tube.
- The tube 72 and the tube 73 each have a petcock 74 connected therewith, and by means of these petcocks the interior of the cylinder 67 can be lubricated without any trouble. The lubrication of the cylinder on the under side of the piston is attained by opening the lower petcock when the piston 66 is at the limit of its descent and pouring the lubricant into the pipe 72, so that with the upward movement of the piston 66 the lubricant will be sucked into the interior of the cylinder, and when the limit of upward movement is reached by closing the petcock the lubricant will be kept in the cylinder. The lubricant is supplied to the cylinder above the piston 66 by opening the upper petcock when the piston is at the limit of its upward stroke and pouring in the lubricant, so that on the downstroke of the piston the lubricant will be drawn into the interior of the cylinder and will remain therein when the petcock is closed. It will thus be seen that the lubricating of the piston is attained without any trouble or inconvenience and through the suction of the piston in the cylinder.
- The main controlling-valve has an outer shell or casing 75, into which is entered the ends of the tubes 72 and 73, as shown in Figs. 8, 9, and 10, and this shell or casing 75 has therein a plug 76, in the body of which is a passage 77 and a passage 78, so arranged as to be brought into communication with a port 79, leading through the casing from the tube 72, and a port 82, leading through the casing from the tube 73 and also to be brought into communication with a port 81, leading through the casing, through which port the exhaust is discharged. The passages 77 and 78 also furnish communication between the ports 79 and 80 and a port 82, which is in communication with a tube 83, leading upward and connected in the arrangement shown with the end of a hose 84, the other end of which is connected with a nipple on the main pressure-supply pipe 85, which pipe has communication also with the interior of the filling-tank 3 at a point above the level of the liquid in the tank, so as to furnish the upper portion of the tank with the required amount of pressure.
- The main shell or casing 75 at its inner end has a threaded stem 86, by means of which the valve as a whole is attached to one of the side bars 16 of the swinging frame. The plug 76 has a stem 87, having adjacent to the end of the plug a shoulder 88, against which abuts a disk 89, encircling the stem, and the

disk 89 is attached to the end of the main shell or casing by draw-bolts 90, so as to hold the plug in place within its chamber in the shell or casing. The outer end of the stem 87 of the plug 76 has entered thereonto a socket 91 of a handle or lever 92 and by means of which the plug can be turned by the operator, so as to shut off communication entirely between the passages 77 and 78 and the ports 79, 80, 81, and 82 or to open communication with the ports 79, 82, 80, and 81 or to open communication between the ports 80 and 82 and the ports 79 and 81, as may be required for admitting pressure to the upper end of the cylinder 67 and exhausting pressure from the lower end of said cylinder or for admitting pressure to the lower end of said cylinder and exhausting pressure from the upper end of said cylinder. The pressure admitted to the upper end of the cylinder 67 operates to force the piston 66 down to carry down the filling-tube into the package, and the pressure admitted into the lower end of the cylinder 67 operates to lift the piston 66 and raise the filling-tube out of the package.

The plate or head 26 on one side of the center head 27 has formed therein a tapered opening or chamber 93, which crosses the passage 41, and this chamber 93 has entered thereto a shell or sleeve 94, having a tapered exterior and interior. The shell or sleeve 94 at its base end has a lip or projection 95, which enters a slot 96, formed in a rim around the chamber 93, by which the shell or sleeve is held in a fixed relation when entered into the chamber, and this lip or projection 95 forms on its inner edge a stop 97, a companion stop 97 being formed on the edge of the shell or sleeve, which stops limit the turning of the plug within the shell or casing. The apex end of the shell or casing 94 has an extension 98 with an exterior screw-thread, which receives a ring-nut 99, by means of which the shell or casing 94 is held within the chamber 93, so as to receive the plug of the valve. The plug 100 of the valve is entered into the interposed shell or casing 94 and is held in the shell or casing by a washer 101 at its apex end, which abuts against the face of the ring-nut 99 and is held in place by a screw 102, the stem of which threads into the end of the plug 100, holding the plug against end movement. The base end of the plug 100 has thereon stop-pins 97^a to coact with the stops 97 and limit the turning of the plug, and extending out from the base end of the plug is a stem 103, the extreme end of which is squared to receive a socket 104 of an arm 105, having at its outer end a pin or pivot 106, to which is connected the lower end of a bar 107, to which bar is connected by pins or pivots 108 a series of trip-arms 109, and the rear end of each trip-arm 109 is attached by a pin or pivot 110 to a fixed bar 111, attached at its upper end to the cross head or bar 22 of the reciprocating frame and at its lower end to the cross bar or plate 23 of the sealing-head. The inner end of each trip-arm 109 has a lateral wing 112, with an inclined upper and lower face, which faces are engaged by the ends of trip-fingers carried by the head 55 of the filling-tube. The inclined upper face of the engaged trip-arm 109 is contacted by the end of a trip-finger 113 on the descent of the head 55 with the descent of the filling-tube, and the inclined under face of the engaged trip-arm is contacted by the end of a trip-finger 114 on the upward movement of the head 55 with the raising of the filling-tube. The trip-arm 113 has in its body a slot 113^a, into which is entered the stem 114^a of the trip-finger 114, and both trip-fingers are mounted on a pivot or pin 115 between ears 116 on the head 55, through which ears 116 and the body of the trip-fingers the pin or pivot 115 passes. The acting end of the trip-finger 113 is held in its normal projected position by the engagement of a tail or extension 117 of its body with the face of the head 55, and the acting end of the trip-finger 114 is held in its normal projected position by the engagement of a tail or extension 118 of its body with the end face of the head 55, so that the acting ends of both fingers are normally held in position to strike the contact-face of the trip-arm 109 which is engaged by the finger. The body of the trip-finger 113 has on its rear face a socket 119, into which is entered the end of a coil-spring 120, the other end of which bears against the face of the head 55 for the spring to act and hold the acting end of the trip-finger in its projected position and at the same time allow of the necessary yield for the acting end to pass the wings of the trip-arms after the arms have been carried down by the engagement of the acting end of the trip-finger 113 with the first trip-arm. The trip-finger 114 has on its rear face a socket 121, into which is entered one end of a spring 122, the other end of which engages the face of the head 55 for the spring to act and hold the trip-finger in its normal projected position and at the same time allow of the necessary yield for the finger to pass the lateral wings of the trip-arms 109 after the trip-arms have been raised by the engagement of the acting end of the trip-finger 114 with the lowermost trip-arm.

The construction shown has pipe 123 leading from a source of pressure-supply, such as an air-compressor or a tank containing compressed air, and this pipe 123 leads into a pressure-regulator 124, from which a pipe 125 leads to the supply-pipe 85, which pipe can have thereon a gage 126 for indicating the pressure in the tank. A coupling 127 is entered into the filling-tank 3 on its under side and has connected therewith a hose 128, 130

the other end of which is connected to a coupling 129 on the head 55, so that the beer or other liquid can flow from the tank through the hose 128 into the head 55 to discharge at the lower end of the filling-tube when the valve 56 of the filling-tube is opened. The weight of the main controlling-valve, with the tubes connected therewith, might throw the swinging frame slightly to one side, so that the sealing-ring would not properly center with the bung or other filling hole of the package, and to overcome this side swing of the frame from the extra weight of the main controlling-valve and tubes a coil-spring 130 is located between the under face of the frame 10 and an ear or ledge 131, projecting out from the side bar 16 of the frame opposite to the main controlling-valve, which spring can be adjusted as to its tension so as to furnish an equipoise for the weight of the valve and other parts, and thereby insure a correct alinement of the sealing-ring with the bung or other filling hole. It is desirable in the filling of packages of different sizes to have the movements of the sealing-head and filling-tube limited correspondingly to the height of the package, as the filling-tube would have considerable waste movement in the difference of travel to enter a full-sized barrel or package and to enter an eighth-sized barrel or package. The movement of the filling-tube is regulated and controlled to correspond with the size of the package to be filled by entering around the stem 65 of the piston above the head 55 of the filling-tube a stop-block 132 made in two halves or sections with an opening 133 on one side for applying the stop-block to the piston rod or stem, so that the piston rod or stem can enter a longitudinal hole 134 in the block. The two sections or halves of the block 132 should be secured together, so that the halves or sections can spread apart in applying the block and be brought together after the block is in position, and for this purpose the two halves or sections of the block are connected on the side opposite to the opening 133, by two spring-clamps, each clamp having a turned end 135 on an arm 136 on each side of a coil 137, so that when the halves or sections of the block are spread apart the spring-clamp is to be under a tension through the arms 136 and coil 135, by which when the block is entered onto the piston stem or rod it will be held in place thereon by the force exerted by the spring-clamps. The length of the block can be varied to suit the size of the package, the smaller the size of the package the longer the block. This stop-block enables the filling-tube to be withdrawn just sufficient for its discharge end to clear the package, so that in the descent of the tube to enter the to-be-filled package the piston will not have to traverse the length of the cylinder, as in the case of a full-sized package. This limiting the movement of the filling-tube to suit the size of packages makes a saving in time required for entering and withdrawing the filling-tube and also a saving in the amount of pressure necessary to operate the piston in inserting and withdrawing the filling-tube.

The operation is as follows: The to-be-filled package is placed on a suitable support and turned so that its bung or filling hole will be in line approximately with the line of descent for the sealing-head and the filling-tube. After the to-be-filled package is placed in position the operator turns the plug 76 of the main controlling-valve, so as to vent the pressure from the under side of the piston 66, which allows the rods 21 to descend, carrying with them the sealing-head and the filling-tube, and the descent continues until the sealing-ring of the sealing-head is fully seated in the bung or other filling hole of the barrel or package to be filled, the sealing-ring being guided to position by the lower end of the sleeve or guard 36. The operator after the sealing-head is fully seated moves the handle or lever a sufficient distance to fully open communication between the ports 80 and 81 through the passage 78, allowing full pressure to flow from the tank through the pipe 83 and pipe 73 into the upper end of the cylinder 67, forcing the piston 66 down, carrying with it the piston-stem, the head 55, and the filling-tube, and such descent of the filling-tube as it approaches the limit of the descent opens the valve 56 by the engagement of the forked arm 61 with the foot or abutment 17, allowing the liquid to flow from the tank through the hose 128 into the head 55 and descend in the filling-tube into the package. The initial descent of the filling-tube causes the end of the trip-finger 113 to strike the wing 112 of the uppermost trip-arm 109, where a full package is to be filled, and such engagement of the trip-finger with the trip-arm forces down the bar 107 and through the arm or handle 105 turns the plug 100 to bring the port 41^b in line with the port 41^a, opening communication between the chamber 40 and the chamber 43, so that pressure from the top of the filling-tank will flow through the tube 51 into the sight-glass and enter the to-be-filled package through the passages 38 and openings 39, equalizing the pressure between the tank and the to-be-filled package. The further descent of the filling-tube and the head 55 does not affect the position of the plug 100, as the ends of the trip-finger 113 will pass the inclined faces of the succeeding wings without changing or modifying the position of the bar 107, with the result that communication remains open between the to-be-filled package and the upper portion of the filling-tank.

The admission of liquid into the package as the liquid rises in the package forces the pressure therein out through the openings 39, passages 38, chamber 40, passage 41, and passage 42 into the sight-glass to return through the tube 51 into the upper portion of the filling-tank, creating a pressure in such tank equal to the amount of air normally present in the to-be-filled package before the 5 pressure is equalized between the filling-tank and the package with the added pressure from the tank to the package for equalizing the pressure. This returned pressure is utilized as the power for operating the piston 66 to raise and lower the filling-tube. The liquid flowing into the package as the package becomes filled passes up through the openings 39, passages or channels 38 into the chamber 40 and through the passage 41 and 10 passage 42 makes its appearance in the sight-glass, and when the liquid is shown in the sight-glass the operator reverses the handle or lever 92, turning it back, so as to establish communication between the passage 77 and 15 ports 79 and 82 for pressure to flow from the tank through the pipe 83 and pipe 72 into the cylinder 67 below the piston and at the same time to open communication between the port 80 and port 81 through the passage 20 78, allowing pressure to vent from the upper portion of the cylinder 67 above the piston for the pressure below the piston 66 to operate and through the piston stem or rod raise the head 55 and filling-tube. The initial 25 upward movement of the head 55 and filling-tube causes the end of the trip-finger 114 to strike the wing 112 of the lowermost trip-arm 109, raising such arm, and with it the bar 107, for the upward movement of the bar 40 through the arm or lever 105 to turn the plug 100, carrying the port 41^b therein out of alignment with the port 41^a and passage 41, shutting off communication between the chamber 40 and the chamber 43, and the further 45 upward movement of the filling-tube and its head 55 does not affect the position of the plug 100, as the end of the trip-finger 114 will strike the under inclined face of the wings above the lowermost one without changing 50 the position of the plug, which remains closed during the continued upward movement of the head 55 and the filling-tube. After the full withdrawal of the filling-tube the frame carrying the sealing-head and filling-tube is 55 swung rearward, so that the operator can insert a bung and close the package, and when closed the filled package is rolled off from the support and a new package placed in position, which package is to be sealed by the descent 60 of the sealing-head and the filling-tube entered thereinto, and the operation just described repeated, such operation being continued until the required number of packages have been filled. 65 The same operation is had in filling smaller- sized packages as in a full barrel or package, and with a half barrel or package the filling-tube and the sealing-head can be operated as described for a full barrel or package, if so desired, though if it is not desired to have the filling-tube make a full movement in entering and withdrawing from the package a stop-block of the proper length can be inserted around the piston stem or rod, so as to limit the upward movement of the filling-tube at a 70 point to just clear the top of the half barrel or package, and, with the stop-block, the trip-finger 113 will first engage the second trip-arm from the top instead of the first trip-arm; but otherwise the operation will be the same. The filling of a quarter barrel or package is attained by using a stop-block around the piston rod or stem, such stop-block being of the requisite length to limit the upward movement of the filling-tube at a point to 75 clear the top or upper side of the quarter barrel or package, and when this is the case the trip-finger 113 will operate on the third trip-arm from the top one; but otherwise the operation will be the same as described for a full barrel or package. The filling of an eighth barrel or package is attained by using a stop-block around the piston stem or rod of sufficient length to limit the upward movement of the filling-tube at a point to clear the 80 top or upper side of the eighth barrel or package, and when this is the case the trip-finger 113 will operate on the lowermost or fourth trip-arm; but otherwise the operation is the same as described for a full barrel or package. 85 The air originally contained in the to-be-filled package cannot escape after the package is sealed, and this original amount of air, with the added pressure from the tank to equalize the pressure between the tank and 90 package, is forced back into the filling-tank, restoring the pressure in such tank, and this pressure is sufficient to furnish the requisite power to operate the piston 66 in the cylinder 67 to raise and lower the filling-tube, so that after the initial start the necessary 95 amount of pressure to operate the filling-tube is obtained from the air originally contained in each to-be-filled package with the added pressure from the tank to the packages without requiring additional pressure to be supplied to the upper portion of the tank. It is preferred to initially charge the tank with and maintain in the tank from a source of pressure-supply the required amount of pressure, as by so doing the tank will contain a sufficient amount of pressure for operative purposes, so that the added pressure from the to-be-filled package compensates for the pressure which is utilized in operating the 100 piston by which the filling-tube is raised and lowered. It is possible to start the apparatus without other pressure than that derived from compressing the air in the tank in supplying the liquid to the tank for use, and 105 110 115 120 125 130

when the apparatus is so used the necessary pressure for operating the piston by which the filling-tube is raised and lowered is obtained from the added pressure forced into the tank from the package as the package is filled with liquid, and after pressure sufficient for the purpose is once obtained such pressure will be maintained so long as the machine is operated in filling packages. It will be seen that the apparatus is capable of operation without a constant supply of outside pressure and that when the apparatus is once under pressure the air-pump, if used, or other source of pressure-supply can be cut out and the machine operated while the packages are filled with the liquid, as the flow of the liquid from the filling-tank into the packages furnishes an amount of pressure sufficient to compensate for the pressure used to operate the filling-tube, thus dispensing with outside power and using no other power than that derived from the pressure forced from the package back into the filling-tank as the package is filled with liquid.

The operation of the apparatus is controlled through a single handle or lever, by which the operator can turn the main pressure-controlling valve so as to open communication between the tank and the cylinder of the piston for raising and lowering the filling-tube as may be required to supply pressure to one end of said cylinder and exhaust pressure from the other end, so that the attention of the operator is only required for the one valve. The valve controlling communication between the filling-tank and the sealing-head is automatically operated with the movements of the filling-tube, with the result that at the initial descent of the filling-tube communication is opened between the filling-tank and the to-be-filled package to equalize the pressure between the tank and the package, and this communication remains open until the package is filled with the liquid, and when filled the operator reverses the main pressure-controlling valve to raise the filling-tube, the initial movement upward of the filling-tube closing communication between the sealing-head and the filling-tank, preventing the escape of pressure from the tank and the admission of liquid into the sight-glass. The small amount of liquid which flows into the sight-glass is forced out in each instance when the controlling-valve for the communication between the filling-tank and the to-be-filled package is opened to equalize the pressure, and this small amount of liquid does not affect in the least the equalizing of the pressure between the filling-tank and the to-be-filled package.

What I regard as new, and desire to secure by Letters Patent, is—

1. In a filling apparatus for liquids, the combination of a tank for containing liquid and pressure, a vertically-sliding frame carry-

ing a sealing-head, a sealing-head having therein an annular chamber and a lateral passage leading therefrom, a filling-tube slidable in and through the sealing-head, a tube connecting the lateral passage in the sealing-head with the tank for inducting and educting pressure between the tank and a to-be-filled package, a piston having a rod for raising and lowering the filling-tube, a cylinder for the piston, means for inducting pressure into and educting pressure from the cylinder, a valve controlling the induction and eduction of pressure into and out from the cylinder, and a valve for the lateral passage in the sealing-head and controlling the communication between the tank and the lateral passage in the sealing-head, said valve automatically actuated with the descent of the filling-tube to open the lateral passage and with the ascent of the filling-tube to close the lateral passage, substantially as described.

2. In a filling apparatus for liquids, the combination of a tank for containing liquid and pressure, a vertically-swinging frame carrying a sealing-head, a sealing-head having therein an annular chamber and a lateral passage leading therefrom, a filling-tube slidable in and through the sealing-head, a tube connecting the lateral passage in the sealing-head with the tank for inducting and educting pressure between the tank and a to-be-filled package, a piston having a rod for raising and lowering the filling-tube, a cylinder for the piston, means for inducting pressure into and educting pressure from the cylinder, a valve-controlling the induction and eduction of pressure into and out from the cylinder, and a valve for the lateral passage in the sealing-head and controlling the communication between the tank and the lateral passage in the sealing-head, said valve automatically actuated with the descent of the filling-tube to open the lateral passage and with the ascent of the filling-tube to close the lateral passage, substantially as described.

3. In a filling apparatus for liquids, the combination of a tank for liquid and pressure, a frame carrying a sealing-head and a filling-tube, a sealing-head having therein a passage, a filling-tube slidable in the sealing-head, a tube connecting the passage in the sealing-head with the tank for inducting and educting pressure, a piston having a rod or stem for raising and lowering the filling-tube, a cylinder for the piston, means for inducting pressure into and educting pressure from the cylinder, a valve controlling the induction and eduction of pressure into and out from the cylinder, a valve controlling the communication between the tank and the passage in the sealing-head, an arm on the valve, a rising and falling bar connected with the arm, trip-bars connected with the rising and falling bar, and trip-fingers moving with

- the filling-tube and engaging the trip-arms for automatically actuating the valve to open and close communication between the tank and sealing-head, substantially as described.
4. In a filling apparatus for liquids, the combination of a tank for liquid and pressure, a frame carrying a sealing-head and a filling-tube, a sealing-head having therein a passage, a filling-tube slidable in the sealing-head, a tube connecting the passage in the sealing-head with the tank for inducing and educting pressure, a piston having a rod or stem for raising and lowering the filling-tube, a cylinder for the piston, means for inducing pressure into and educting pressure from the cylinder, a valve controlling the induction and eduction of pressure into and out from the cylinder, a valve controlling the communication between the tank and the passage in the sealing-head, an arm on the valve, a rising and falling bar connected with the arm, an upper trip-arm and a lower trip-arm both connected with the rising and falling bar, a trip-finger engaging the upper trip-arm, a trip-finger engaging the lower trip-arm, both fingers moving with the filling-tube and engaging the trip-arms for the engagement of the upper trip-arm and its trip-finger to automatically open and for the engagement of the lower trip-arm, with its trip-finger to automatically close communication between the tank and sealing-head, substantially as described.
5. In a filling apparatus for liquids, the combination of a tank for liquid and pressure, a frame carrying a sealing-head and a filling-tube, a sealing-head having therein a passage, a filling-tube slidable in the sealing-head, a tube connecting the passage in the sealing-head with the tank for inducing and educting pressure, a piston having a rod or stem for raising and lowering the filling-tube, a cylinder for the piston, means for inducing pressure into and educting pressure from the cylinder, a valve controlling the induction and eduction of pressure into and out from the cylinder, a valve controlling the communication between the tank and the passage in the sealing-head, an arm on the valve, a rising and falling bar connected with the arm, a plurality of trip-arms each arm connected with the rising and falling bar, a trip-finger engaging the upper trip-arm, a trip-finger engaging the lower trip-arm, both fingers moving with the filling-tube and engaging the trip-arms, means for limiting the upward movement of the filling-tube for enabling the trip-fingers to engage the proper trip-arm corresponding to the position of the filling-tube in relation to the to-be-filled package and have the upper or engaged trip-arm and its trip-finger automatically open and for the engagement of the lower trip-arm with its trip-finger automatically close communica-
- tion between the tank and sealing-head, substantially as described.
6. In a filling apparatus for liquids, the combination of a tank for containing liquid and pressure, a sealing-head for the to-be-filled package and having therein a chamber with a lateral passage leading therefrom, furnishing communication with the interior of the to-be-filled package, a valve entered into and controlling the lateral passage of the sealing-head, a tube connecting the lateral passage of the sealing-head with the tank for inducing and educting pressure between the tank and the to-be-filled package, a filling-tube slidable through the sealing-head, a piston having a rod or stem for reciprocating the filling-tube, a cylinder for the piston, a tube leading from the upper end of the cylinder, a tube leading from the lower end of the cylinder, a main valve controlling the induction of pressure into and the eduction of pressure from the cylinder through the tubes, and a tube between the controlling-valve and the tank for actuating the piston and lowering and raising the filling-tube, substantially as described.
7. In a filling apparatus for liquids, the combination of a tank for containing liquid and pressure, a sealing-head for the to-be-filled package and having therein a chamber with a lateral passage leading therefrom furnishing communication with the interior of the to-be-filled package, a valve entered into and controlling the lateral passage of the sealing-head, a tube connecting the lateral passage of the sealing-head with the tank for inducing and educting pressure between the tank and the to-be-filled package, a filling-tube slidable through the sealing-head, a piston having a rod or stem for reciprocating the filling-tube, a cylinder for the piston, a tube leading from the upper end of the cylinder, a tube leading from the lower end of the cylinder, a main valve-casing having on opposite sides ports connected with the tubes leading from the piston-cylinder, a port in the casing of the valve for inducing pressure from the tank, an exhaust-port in the casing of the valve, a valve-plug having passages for connecting the ports of the valve-casing with the tank, and a tube between the controlling-valve and the tank, substantially as described.
8. In a filling apparatus for liquids, the combination of a supporting-frame, a pair of rods slidable in the frame, a cross-bar at the lower end of the slidable rods, a filling-tube slidable through the cross-bar, a stuffing-box on the upper side of the cross-bar around the filling-tube, a sleeve detachably entered into the lower side of the cross-bar around the filling-tube and having in its inner face a series of longitudinal passages and having a convex lower end, a packing-ring surrounding the

- sleeve above its lower end and entered into the under side of the cross-bar, a chamber in the cross-bar around the filling-tube, and having a lateral passage leading therefrom 5 and in communication with the passages of the sleeve, for sealing the filling-hole of a to-be-filled package and furnishing communication for inducting and educting pressure, substantially as described.
- 10 9. In a filling apparatus for liquids, the combination of sliding rods, a cross-bar at the lower end of the rods, a filling-tube, a stuffing-box on the upper side of the cross-bar around the filling-tube, a sleeve entered 15 into the lower side of the cross-bar around the filling-tube and having a convex lower end and a series of ribs on its interior face forming a plurality of passages each passage opening through the lower end of the sleeve, 20 and a packing-ring surrounding the sleeve above its lower end and entered into the under side of the cross-bar for sealing the filling-hole of the package, substantially as described.
- 25 10. In a filling apparatus for liquids, the combination of sliding rods, a cross-bar at the lower end of the rods, a filling-tube, a stuffing-box on the upper side of the cross-bar around the filling-tube, a sleeve entered 30 into the lower side of the cross-bar around the filling-tube and having a convex lower end and a series of ribs on its interior face forming a plurality of passages each passage opening through the lower end of the sleeve, 35 a packing-ring surrounding the sleeve above its lower end and entered into the under side of the cross-bar for sealing the filling-hole of the package, a chamber in the cross-bar around the filling-tube, and a lateral passage 40 leading from the chamber, substantially as described.
11. In a filling apparatus for liquids, the combination of sliding rods, a cross-bar at the lower end of the rods, a filling-tube, a stuffing-box on the upper side of the cross-bar around the filling-tube, a sleeve entered 45 into the lower side of the cross-bar around the filling-tube and having a convex lower end and a series of ribs on its interior face forming a plurality of passages each passage opening through the lower end of the sleeve, 50 a packing-ring surrounding the sleeve above its lower end and entered into the under side of the cross-bar for sealing the filling-hole of the package, a chamber in the cross-bar around the filling-tube, and a lateral passage 55 leading from the chamber, substantially as described.
12. In a filling apparatus for liquids, the combination of sliding rods, a cross-bar at the lower end of the rods, a filling-tube, a stuffing-box on the upper side of the cross-bar around the filling-tube, a sleeve entered 60 into the lower side of the cross-bar around the filling-tube and having a convex lower end and a series of ribs on its interior face forming a plurality of passages each passage opening through the lower end of the sleeve, 65 a packing-ring surrounding the sleeve above its lower end and entered into the under side of the cross-bar for sealing the filling-hole of the package, a chamber in the cross-bar around the filling-tube, a lateral passage leading from the chamber, a valve controlling the lateral passage and automatically operated, a tube in communication with the lateral passage, and a filling-tank for liquid and pressure, substantially as described.
13. In a filling apparatus for liquids, the combination of a tank for liquid and pressure, a frame having at each end a journal mounted on the supporting-frame of the tank, a plate having a journal on each side mounted in journal-boxes on the frame, side bars depending from the plate, a spring on one side bar between the frame and a shelf on the 90 side bar, a cylinder carried by the plate, a piston in the cylinder, a piston rod or stem, sliding rods passing through the plate, a cross-bar on the lower end of the sliding rods, a sealing-head on the cross-bar through 95 which the filling-tube passes, a tube leading from the tank to a passage in the sealing-head, a tube leading from the upper end of the cylinder, a tube leading from the lower end of the cylinder, a main controlling-valve 100 having the tubes of the cylinder in communication therewith, and a tube leading from the main controlling-valve to the tank, substantially as described.
14. In a filling apparatus for liquids, the combination of a tank for liquid and pressure, a sealing-head having therein a passage furnishing communication with a to-be-filled package, a tube furnishing communication between the passage of the sealing-head and the tank, a valve controlling communication between the sealing-head and the tank, a filling-tube slidable in the sealing-head, a head on the upper end of the filling-tube, a rising and falling bar connected with the valve controlling the communication between the sealing-head and the tank, trip-arms pivotally connected with the rising and falling bar, a downwardly-projecting trip-finger, and an upwardly-projecting trip-finger, both mounted on the head of the filling-tube and operating with the descent of the head of the filling-tube for the downwardly-projecting trip-finger to engage the uppermost one of the trip-arms and turn the valve controlling communication between the sealing-head and tank to open communication and for the upwardly-projecting trip-finger to engage the lowermost trip-arm and turn the valve controlling communication between 130

the sealing-head and the tank to close communication, substantially as described.

15. In a filling apparatus for liquids, the combination of a tank for liquid and pressure, a sealing-head having therein a passage furnishing communication with a to-be-filled package, a tube furnishing communication between the passage of the sealing-head and the tank, a valve controlling communication between the sealing-head and the tank, a filling-tube slidable in the sealing-head, a head on the upper end of the filling-tube, a rising and falling bar connected with the valve controlling the communication between the sealing-head and the tank, trip-arms pivotally connected with the rising and falling bar, a downwardly-projecting trip-finger, an upwardly-projecting trip-finger, a spring for normally holding the downwardly-projecting trip-finger in operative position.

and a spring for normally holding the upwardly-projecting trip-finger in operative position, both trip-fingers mounted on the head of the filling-tube and operating with the descent of the head of the filling-tube for the downwardly-projecting trip-finger to engage the uppermost one of the trip-arms and turn the valve controlling communication between the sealing-head and tank to open communication and for the upwardly-projecting trip-finger to engage the lowermost trip-arm and turn the valve controlling communication between the sealing-head and the tank to close communication, substantially as described. 25 30
